UNITED STATES PATENT OFFICE

CHARLES H. CAMPBELL, OF BROOKLINE, MASSACHUSETTS

DESIGN FOR AN EMBOSSED SHEET METAL COVER FOR BOXES, CANS, AND THE LIKE

Application filed December 12, 1929. Serial No. 33,756. Term of patent 14 years.

To all whom it may concern:

Be it known that I, CHARLES H. CAMPBELL, a citizen of the United States, residing at Brookline, in the county of Norfolk and State of Massachusetts, have invented a new, original, and ornamental Design for Embossed Sheet-Metal Covers for Boxes, Cans, and the like, of which the following is a specification, reference being had to the accompanying drawings, forming a part thereof.

In the drawings,—

Fig. 1 is a perspective view of an embossed sheet metal cover for substantially rectangular boxes or cans and the like;

Fig. 2 is a plan view of said cover;

Fig. 3 is a longitudinal sectional view thereof taken on line 3—3 of Fig. 2.

I claim:

The ornamental design for an embossed sheet metal cover for boxes, cans and the like as shown.

CHARLES H. CAMPBELL.
